UNITED STATES PATENT OFFICE.

LOUIS SCHWITZER, OF INDIANAPOLIS, INDIANA.

PUMPING SYSTEM FOR GAS-ENGINES.

1,109,256.

Specification of Letters Patent.

Patented Sept. 1, 1914.

Application filed June 3, 1912. Serial No. 701,231.

To all whom it may concern:

Be it known that I, LOUIS SCHWITZER, a citizen of Austria, (who has declared his intention of becoming a citizen of the United States,) residing at Indianapolis, in the county of Marion and State of Indiana, have invented a new and useful Pumping System for Gas-Engines, of which the following is a specification.

10 The object of my invention is to provide a compact and simplified construction arrangement of oil pump and air pump for gas engines.

15 The construction is primarily designed for use in that type of engine in which the flow of gases is controlled by valve sleeves arranged within the cylinder, between the cylinder wall and the piston, but portions of the details of construction of my improvements 20 are applicable to other types of engines.

The accompanying drawings illustrate my invention.

Figure 1 is an axial vertical section of an 25 engine embodying my invention; Fig. 2 is a fragmentary side elevation; Fig. 3 an axial section of the oil pump.

In the drawings, 10 indicates an engine cylinder having an open lower end to which 30 is secured the upper open end of the main crank shaft casing 11, to the lower open end of which is secured a complementary crank casing or drainage pan 12, to the lower end of which is secured an oil reservoir 13 35 within which is formed an oil pump 14.

Mounted within cylinder 10 is a valve sleeve 15 and within the valve sleeve 15 is a second valve sleeve 16 within which is a piston 17 which is connected by a pitman 40 18 to the main crank shaft 19 which is journaled in bearings 21, preferably supported by the casing member 11. Also journaled in the casing member 11 is a valve shaft 22 which is provided with two cranks for each 45 pair of valve sleeves 15 and 16, the said cranks being connected by suitable arms 23 to the respective sleeves.

Opposite one of the cranks of the valve shaft, the casing 11 is provided with an extension 24 which, at its lower end, is provided with an opening 24 which is flanked externally by an inclined face 26 to which the open end of the main body 27 of the lubricant pump is detachably bolted. The vertical face of the extension 24 is conveniently provided with a gage 28 and at its

upper end this extension is provided with a vertical hole 29 which receives the lower end of the main body 31 of an air pump. A plug 32 is threaded into the upper end 60 of the body 31 so as to be readily adjusted longitudinally of the pump body to vary the compression space therein. Reciprocably mounted within the cylindrical bore of the pump body 31 is a piston 33 which is provided with a longitudinal bore 34 open at its upper end and near its lower end provided with a transverse passage 35 which, when the piston is at the compression end of its stroke, will register with an exhaust 70 passage 36 which delivers to a pipe 37 carried to the fuel tank (not shown).

The pump body 27 is provided in its lower part with a cylindrical bore 41 within which is mounted an oscillatable cylindrical valve 42. Plugs 43, 43 are threaded into the opposite ends of bore 41 and serve to hold the valve 42 axially in place. Extending longitudinally within valve 42, for the greater portion of its length, is a passage 44 which may be conveniently formed by drilling from end to end and closing the ends by plugs 45, 45. Communicating with one end of passage 44 and opening out through the circumference of the piston, 80 is a discharge passage 46, and I prefer to provide a similar discharge passage 46 at the opposite end of the piston, thus making the structure fool-proof in that it may be placed either end foremost within bore 41 85 without interfering with its proper operation. Leading into passage 44 is an inlet passage 47 arranged for intermittent registry with an inlet passage 48 formed through the bottom of the pump body 27 95 and threaded to receive a coupling 49 which, in turn is connected to one end of a coil 51, the other end of which is connected by a coupling 52 with a passage 53 formed through the body of one wall of pan 12 100 and communicating at its lower end with an inlet pipe 54 which leads downwardly into the coil sump 14. Opposite passage 48 the valve 42 is provided with a transverse threaded opening 55 which receives the 105 threaded shank of a pump body 56 having a bore 57 within which is reciprocably mounted a pump piston 58. That one of the valve operating arms 23 which lies opposite the projection 24, is provided with a downwardly and outwardly extending arm 61 110 which is pivotally connected at 62 to the

piston 58 and at 63 to a link 64, the upper end of which is pivoted to the air pump piston 33.

Rotation of shaft 22 (which is, of course, connected in any usual manner to the main crank shaft 19 so as to be driven thereby) for the purpose of operating the valve sleeves 15 and 16, will result in such a movement of the arm 61 that the point 62 will travel through a substantially elliptical path, as indicated by the dotted line in Fig. 1, and this will result in a simultaneous reciprocation of the piston 58 and an oscillation of the valve 42 so as to intermittently and alternately register the inlet passage 47 with passage 48 and the exhaust passage 46 with an oil delivery passage 65 which leads the discharged oil to any desired point, such, for instance, as the equalizing chamber 66, from which it may be delivered to desired points. At the same time the points 63 of arm 61 will travel through a different ellipse and will result in a reciprocation of the air pump piston 33, this reciprocation resulting in a delivery of air under pressure to the fuel tank. The maximum pressure of delivered air from the pump chamber 31 may be determined by an adjustment of the adjustable head or plug 32 and, of course, whenever the pressure in the chamber to which pipe 37 delivers becomes equal to the pressure of compression in the air pump there will be no further delivery of air from the air pump even though the piston 35 be continued in operation.

The pump bodies 27 and 31 are readily accessible and readily detachable from position so that they may be easily withdrawn for inspection and repair.

40 I claim as my invention:

1. In an internal combustion engine, the combination with a cylinder, piston and interposed longitudinally shiftable valve sleeve, of a valve shaft having an eccentric portion, a connecting arm connecting said eccentric portion and the valve sleeve; an oil pump comprising an oscillatory valve member and a reciprocatory plunger carried by said valve member, a connection between the connecting arm and the reciprocatory plunger of the oil pump, an air pump having a reciprocating member, and a connection between said reciprocating member and the connecting arm.

55 2. In an internal combustion engine, the combination with a cylinder, piston and interposed longitudinally shiftable valve sleeve, of a valve shaft having an eccentric portion, a connecting arm connecting said eccentric portion and the valve sleeve, an oil pump, a connection between the connecting arm and the oil pump, an air pump having a reciprocating member, and a connection between said reciprocating member and the connecting arm.

3. In an internal combustion engine, the combination with a cylinder, piston and interposed longitudinally shiftable valve sleeve, of a valve shaft having an eccentric portion, a connecting arm connecting said eccentric portion and the valve sleeve, an oil pump comprising an oscillatory valve member and a reciprocatory plunger carried by said valve member, a connection between the connecting arm and the reciprocatory plunger of the oil pump. 75

4. In an internal combustion engine, the combination with a cylinder, piston and interposed longitudinally shiftable valve sleeve, of a valve shaft having an eccentric portion, a connecting arm connecting said eccentric portion and the valve sleeve, an oil pump, a connection between the connecting arm and the oil pump. 80

5. In an internal combustion engine, the combination with a casing member having an external extension, an oil pump body detachably connected to said extension, and having a cylindrical bore, a cylindrical valve member oscillatably mounted in said bore and having a passage therethrough with an inlet end and an exhaust end, and the pump body having an inlet passage and an exhaust passage arranged for alternate registry with the inlet and exhaust ends of the passage through the valve, a pump cylinder carried by the valve member and projecting substantially radially therefrom, and a pump piston reciprocably mounted within said pump chamber, a shaft journaled within the casing member and provided with an eccentric portion, and a connection between said eccentric portion and the pump piston, an axially shiftable valve sleeve arranged within the engine cylinder and embracing the piston thereof, and a connection between the connecting arm of the pump piston and said last mentioned valve sleeve. 95

6. In an internal combustion engine, the combination with a casing member having an external extension, an oil pump body detachably connected to said extension, and having a cylindrical bore, a cylindrical valve member oscillatably mounted in said bore and having a passage therethrough with an inlet end and an exhaust end, and the pump body having an inlet passage and an exhaust passage arranged for alternate registry with the inlet and exhaust ends of the passage through the valve, a pump cylinder carried by the valve member and projecting substantially radially therefrom, and a pump piston reciprocably mounted within said pump chamber. 110

7. In an internal combustion engine, the combination with a casing member having an external extension, an oil pump body detachably connected to said extension, and having a cylindrical bore, a cylindrical valve member oscillatably mounted in said bore 115 120 125 130

and having a passage there through with an inlet end and an exhaust end, and the pump body having an inlet passage and an exhaust passage arranged for alternate registry with the inlet and exhaust ends of the passage through the valve, a pump cylinder carried by the valve member and projecting substantially radially therefrom, and a pump piston reciprocably mounted within said pump chamber, a shaft journaled within the casing member and provided with an eccen-

tric portion, and a connection between said eccentric portion and the pump piston.

In witness whereof, I have hereunto set my hand and seal at Indianapolis, Indiana, 15 this 31st day of May, A. D. one thousand nine hundred and twelve.

LOUIS SCHWITZER. [L.S.]
